UNITED STATES PATENT OFFICE

AMSON FURTSCH, OF NEW YORK, N. Y.

DESIGN FOR A BUCKLE OR SIMILAR ARTICLE

Application filed February 11, 1933. Serial No. 47,182. Term of patent 3½ years.

To all whom it may concern:

Be it known that I, AMSON FURTSCH, a citizen of the United States, residing in the city, county and State of New York, have invented a new, original, and ornamental Design for a Buckle or Similar Article, of which the following is a specification, reference being had to the accompanying drawing, forming part thereof.

Fig. 1 is a front view of a buckle or similar article showing my new design, as it appears when applied to a garment or belt.

Fig. 2 is a top plan view of the article shown in Fig. 1.

Fig. 3 is a plan view of my buckle or similar article, showing my new design.

I claim:

The ornamental design for a buckle or similar article, as shown and described.

AMSON FURTSCH.
